ABSTRACT OF THE DISCLOSURE

Propanesultone is stabilized by adding at least one compound selected from the group consisting of aliphatic amines, alicyclic amines, aralkylamines, non-aromatic cyclic amines, N-alkyl-substituted aromatic amines, aminoalcohols, amine character nitrogen containing carboxylic acids having 2 to 10 carbon atoms and their esters, amides, pyridines, quinolines, and reaction products of these compounds with propanesultone.

DETAILED DESCRIPTION OF THE INVENTION

Field of the invention

The present invention relates to a process for stabilizing the hue of propanesultone.

Description of the prior art

Propanesultone is a colorless liquid or crystal having a melting point of 31° C. This compound is an important synthetic material used widely as an agent for improving the dye-ability of synthetic fibers, as a surfactant, as an additive for modified starch, etc. However, propanesultone becomes colored gradually to light yellow or, in extreme cases, to orange or reddish brown during storage and transportation at ambient temperature, or under heating, so that its commercial value is reduced. Although the prevention of coloring of propanesultone has been long sought, a satisfactory process for doing so has not been found yet.

SUMMARY OF THE INVENTION

After intensive investigations on preventing the coloring of propanesultone, we have found that compounds selected from the group consisting of aliphatic amines, alicyclic amines, aralkylamines, non-aromatic cyclic amines, N-alkyl substituted aromatic amines, aminoalcohols, amine character nitrogen containing carboxylic acids having 2 to 10 carbon atoms and their esters, amides, pyridines, quinolines, and reaction products of these compounds with propanesultone have quite excellent properties for stabilizing propanesultone. The present invention has been accomplished on the basis of this finding.

The object of the invention is to provide a process for stabilizing propanesultone by adding one or more of said stabilizer compounds to propanesultone to inhibit coloring and deterioration of propanesultone at ambient temperature or at an elevated temperature for a long period of time.

As examples of the stabilizers used in the process of the present invention, there may be mentioned the following compounds.

a. Aliphatic amines: Primary amines (RNH_2), secondary amines ($RR'NH$) and tertiary amines ($RR'R''N$), in which R , R' and R'' each is alkyl having 1 to 20 carbon atoms, or allyl, such as mono-, di- and tri-ethylamine, n-propylamine, isopropylamine, n-butylamine, etc.

b. Alicyclic amines: Primary, secondary or tertiary amines, as set forth in (a), in which one of the R groups is a saturated ring having from 3 to 7 carbon atoms in the ring and which may be substituted on the ring by hydrocarbons, such as cyclohexylamine, methylcyclohexylamine, etc.

2

c. Aralkylamines: Amines as set forth in (a), in which one of the R groups is (Ar)(Alk)—, wherein Ar is phenyl and Alk is an alkylene group of 1 to 6 carbon atoms, such as benzylamine phenethylamine, etc.

5 d. Non-aromatic cyclic amines: Cyclic compounds containing in the ring at least 1 nitrogen atom, such as pyrrolidine, morpholine, piperidine, piperazine, hexamethylenetetraamine, melamine, etc.

e. N-alkyl substituted aromatic amines: Compounds of the formula $ArNR_1R_2$, wherein Ar is phenyl or phenyl substituted with a hydrocarbon group, at least one of R_1 and R_2 is alkyl having from 1 to 6 carbon atoms and the other of R_1 and R_2 is alkyl having 1 to 6 carbon atoms or H, such as N-methylaniline and N,N-dimethylaniline, etc.

10 f. Aminoalcohols: Compounds according to (a), in which at least one of R , R' and R'' is substituted with OH, such as mono-, di- and tri-ethanolamine, propanolamine, 2-amino-2-methylpropanol-(1), etc.

15 g. Amine character nitrogen containing carboxylic acids having 2-10 carbon atoms and their esters: Nitrilotriacetic acid, nicotinic acid, methyl nicotinate, methyl picolinate, etc.

20 h. Amides: Formamide, dimethylformamide, acetamide, acrylamide, p-toluene-sulfonamide, nicotinic acid amide, α -pyrrolidone, ϵ -caprolactam, etc.

25 i. Pyridines: Pyridine and pyridine substituted on the ring with alkyl groups having 1 to 6 carbon atoms, such as pyridine, picoline, (α , β , or γ), 2-methyl-5-ethylpyridine, etc.

30 j. Quinolines: Quinoline and quinoline substituted on the ring with alkyl groups having 1 to 6 carbon atoms, such as quinoline, methylquinoline, etc.

35 k. Reaction products of propanesultone: Reaction products of the above compounds (a) through (j) with propanesultone.

The stabilized propanesultone composition of the present invention may be obtained easily by directly adding and dissolving or partially dissolving the stabilizer or stabilizers in liquid propanesultone.

40 From the viewpoints of the influence of the stabilizers on the purity of the propanesultone, the stabilizing effect thereof and economy, the preferred amount of the stabilizer added to propanesultone is 0.01-1% by weight, based on the weight of the propanesultone treated. If necessary, two or more stabilizers may be used together in the process of the present invention.

45 The most preferred direct method of evaluating the stability of propanesultone or the stabilizing effect of the stabilizer for propanesultone comprises allowing a sample to stand under ordinary storage conditions for a long period of time and determining the color change that occurs. However, this method is inconvenient, because it requires a long period of time for the evaluation. Therefore, the stabilizing effects were compared according to an accelerated coloring test under the following special conditions.

50 Accelerated coloring test under heating: Thirty (30) grams of propanesultone sample were charged into a hard glass ampoule, which was then closed by fusion. The ampoule was allowed to stand at 120° C. for a predetermined period of time. The hue of the sample was determined by measuring the Gardner number or APHA number thereof.

55 The process of the present invention will be further illustrated by the following representative Examples.

Example 1

60 Samples were prepared by mixing freshly prepared propanesultone (hue: Gardner No. 1, purity: about 99%) with 0.1 wt. percent of each of the stabilizers listed in Table 1 and were subjected to an accelerated coloring test under heating. For comparison, propanesultone containing

no stabilizer and propanesultone containing the same amount of representative phenolic stabilizers were tested in the same manner. The results are shown in Table 1. The numerical values in the Table are Gardner numbers. The heating was effected in all cases at 120° C. for 90 minutes.

TABLE 1

Additive	Hue after test	
Aliphatic amines:		
Monoethylamine (70%)	2	
Diethylamine	3	10
Triethylamine	3	
n-Propylamine	3	
Isopropylamine	3	
n-Butylamine	3	
Alicyclic amines:

β-Picoline	3	
γ-Picoline	3	
2-Methyl-5-ethylpyridine	3	
Quinolines:		
Quinoline	2	60
Methylquinoline	2	
Reaction products with propanesultone:		
Reaction product of propanesultone and triethanolamine	4	
Reaction product of propanesultone and pyridine	3	
Controls:		
No additive	6	
Hydroquinone	6	
2,3-Dimethylphenol	7	
3,5-Dimethylphenol	9	
p-Methoxyphenol	6	
Guaiacol	6	
Styrenated phenol	7	
Butylphenol	7	75

As is clearly shown in Table 1, coloration of propanesultone containing any of the stabilizers according to the present invention was less than the coloration of propanesultone per se. On the other hand, coloration of propanesultone containing a phenolic stabilizer was substantially the same as or more highly colored than was the case when no additive was used.

Example 2

Samples of freshly prepared propanesultone (hue: Gardner No. 2, purity: above 99%) were mixed with 0.1 wt. percent of each of N,N'-dimethylpiperazine, triethanolamine, methyl picolinate, pyridine and β-picoline and were subjected to the accelerated coloring test under heating. The change in hue was measured at hourly intervals over a period of 5 hours. The results are shown in Table 2. The numerical values in the Table are Gardner numbers.

TABLE 2

Additive	Heating time (hours)					
	0	1	2	3	4	5
No additive	2	3	4	6	8	10

Methylpicolinate	2	2	2	3	4	5
Pyridine	2	2	2	3	4	5
β-Picoline	2	2	3	3	4	5

Example 3

Samples of freshly prepared propanesultone (hue: Gardner No. 2, purity: above 99%) were mixed with various amounts in the range of 0.05-1 wt. percent of (1) triethanolamine and (2) pyridine and were subjected to the accelerated coloring test under heating for 5 hours. The results are shown in Table 3. The numerical values in the Table are Gardner numbers.

	0.50	2	2	2	2	2.5	3
	1.00	2	2	2	2	2.5	2.5

Example 4

Accelerated coloring tests were carried out previously to obtain some samples of propanesultone, the hues of which were different from one another. The samples were mixed with 0.1 wt. percent of (1) triethanolamine and (2) pyridine and were allowed to stand at room temperature for 200 days and the degrees of coloring were examined at the intervals stated in the following table. In the same manner, propanesulfone containing no additive was also tested as a control. The results are shown in Table 4. The numerical values in the Table are APHA numbers.

TABLE 4

As clearly shown in Table 4, a remarkable correlation exists between the values obtained in the accelerated heating test and the degree of coloring after allowing the samples to stand for an extended period of time. It is noted that triethanolamine and pyridine both have an excellent stabilization effect, i.e., an effect of preventing coloring of propanesultone samples of a wide range of quality.

Example 5

Reaction products of the stabilizers (a) through (j) with propanesultone were prepared by selecting a compound (A) from each of the respective groups (a) to (j) and reacting the same with propanesultone in an equimolar ratio. The reaction products (B) thus obtained were washed with a non-solvent to remove unreacted substances. As an example, 4.9 grams (0.04 mol) of propanesultone were weighed into a 50 ml. conical flask. 3.2 grams (0.04 mol) of pyridine were added dropwise and, after the addition, it was stirred. The mixture was left stand overnight. The formed crystals were washed with methanol repeatedly to remove unreacted substances and then they were dried under a reduced pressure.

Samples were prepared by mixing freshly prepared propanesultone (hue: Gardner No. 2, purity: above 99%) with each reaction product (B) in an (1) amount of 0.1% by weight calculated on the basis of the reaction products (B) and (2) an amount of 0.1% by weight calculated on the basis of the compounds (A) which were reacted with propanesultones to make reaction products (B). The samples were subjected to the accelerated coloring test under heating. For comparison, propanesultone containing 0.1% by weight of each of the compounds (A) and propanesultone containing no stabilizer were tested in the same manner. The results are shown in Table 5. The numerical values in the Table are Gardner numbers. The heating was effected in all cases at 120° C. for 90 minutes.

The embodiments of the invention in which an exclusive property or privilege is claimed are defined as follows:

1. The process for stabilizing propanesultone, which consists essentially of mixing with propanesultone from about 0.01 to 1% by weight, based on the weight of propanesultone, of at least one stabilizer compound selected from the group consisting of

- a. primary amines RNH_2 , secondary amines $\text{RR}'\text{NH}$ and tertiary amines $\text{RR}'\text{R}''\text{N}$, in which R, R' and R'' each is alkyl having 1 to 20 carbon atoms, or allyl;
- b. primary, secondary or tertiary amines, as set forth in a, in which one of the R groups is a saturated hydrocarbon ring having from 3 to 7 carbon atoms in the ring and which can be substituted on the ring by methyl radicals;
- c. amines as set forth in a, in which one of the R groups is (Ar) (Alk)—, wherein Ar is phenyl and Alk is an alkylene group of 1 to 6 carbon atoms;
- d. nonaromatic cyclic amines containing in the ring at least one nitrogen atom selected from the group pyrrolidine, morpholine, piperidine, piperazine, $\text{N,N}'$ -dimethyl - piperazine, hexamethylenetetraamine and melamine;
- e. compounds of the formula ArNR_1R_2 , wherein Ar is phenyl, at least one of R_1 and R_2 is alkyl having from 1 to 6 carbon atoms and the other of R_1 and R_2 is alkyl having 1 to 6 carbon atoms or H;
- f. compounds according to a, in which at least one of R, R' and R'' is substituted with OH;
- g. amine-character-nitrogen containing carboxylic acids having 2-10 carbon atoms and their esters selected from the group nitrilotriacetic acid, nicotinic acid, methyl nicotinate and methyl picolinate;
- h. amides selected from the group formamide, dimethylformamide, acetamide, acrylamide, p-toluenesulfon-
